Attorney

UNITED STATES PATENT OFFICE.

DAVID F. VAUGHAN, OF RIVERTON, NEW JERSEY.

ANTICREEPER FOR RAILROAD-RAILS.

1,180,891.

Specification of Letters Patent. Patented Apr. 25, 1916.

Application filed October 1, 1915. Serial No. 53,502.

To all whom it may concern:

Be it known that I, DAVID F. VAUGHAN, a citizen of the United States, residing at Riverton, in the county of Burlington and State of New Jersey, have invented certain new and useful Improvements in Anti-creepers for Railroad-Rails, of which the following is a specification.

My invention relates to improvements in anticreepers for railroad rails, which are adapted to grip the rails and engage a stationary part of the road bed and prevent the forward longitudinal displacement or the creeping of the rails.

The object of my invention is to provide an anticreeper of novel, simple and efficient construction adapted to embrace the rail base and to grip the same when the upper portion of the anticreeper is canted forwardly in combination with a spring formed independently of the anticreeper and maintained in such operative position that it will act against the rail and against the anticreeper and tend to cant the upper portion 25 of the anticreeper forwardly and thereby maintain the anticreeper in gripping engagement with the rail and in constant readiness for action under all conditions, so that when the rail tends to creep and the 30 lower portion of the anticreeper engages the stationary part of the road bed, the pressure of the anticreeper against the said stationary part will cause the anticreeper to increase its grip upon the rail.

With this object in view, the invention consists of the elements and the combinations of them hereinafter fully described and claimed.

In the accompanying drawings, illustrating my invention: Figure 1 is a plan view of a portion of a railroad rail, a portion of a cross-tie supporting the same, and my improved anticreeper applied to the rail. Fig. 2 is a side elevation of the parts shown in Fig. 1. Fig. 3 is a transverse section through the rail, on line 3-3 of Fig. 2. Fig. 4 is a transverse section through the rail and the anticreeper, on line 4-4 of Fig. 3.

Referring to the drawings, 2 designates a portion of a railroad cross-tie and 5 a railroad rail of usual construction. The cross-tie 2 forms a stationary part of the road bed which supports the rail 5 and over which the rail tends to creep under the well known conditions.

My improved anticreeper is supported by the rail base 6 and is of the following construction: 7 designates a jaw member which embraces one side of the rail base 6 and comprises an upper part 8 extending over the rail base, a lower part 9 extending under the rail base, and a part 10 outwardly of the rail base and connecting the parts 8 and 9. When herein I speak of forwardly I mean the direction in which the rail tends to creep, as indicated by the arrows in Figs. 1, 2 and 4. The lower forward corner 11 of the upper part 8 of the member 7 is adapted to engage the top of the rail base 6 and the upper rearward corner 12 of the lower part 9 of the member 7 is adapted to engage the bottom of the rail base 6 and grip the rail base when pressure is applied to the member 7 tending to cant the upper portion thereof forwardly and the lower portion thereof rearwardly. The lower part 9 of the member 7 extends down a suitable distance from the bottom of the rail 5 and forms an abutment 13 adapted to engage the cross-tie 2 when the rail 5 tends to creep forwardly. As the rail tends to creep, and thus forces the abutment 13 against the cross-tie 2, the pressure of the abutment against the cross-tie will tend to cant the member 7 and thus force the corners 11 and 12 into gripping engagement with the rail base 6; and the greater the tendency of the rail to creep the greater will be the grip of the member 7 upon the rail, preventing the creeping thereof. The member 7 is provided with an arm 14 which extends rearwardly from the upper part 8 thereof and over the rail base 6. The bottom of the arm 14 has a socket 15 formed therein, as shown; and inserted into the socket 15 is a spring 16, preferably helical in form, which exerts downward pressure upon the rail base 6 and upward pressure against the arm 14 and tends to cant the upper portion of the member 7 forwardly. This pressure of the spring 16 forces the corners 11 and 12 against the rail base 6 and holds the anticreeper in gripping engagement with the rail and in constant readiness for action at all times and under all conditions.

To prevent outward displacement of the jaw member 7 from the rail base 6, I provide the lower part 9 of the member 7 with an arm 17 which extends transversely beneath the rail base 6 and which is provided with

an upwardly extending part or tooth 18 adapted to engage the opposite side of the rail base 6 and prevent such displacement. This part or tooth 18 is maintained above the bottom of the rail base 6 by the pressure of the spring 16 which tends to raise the arm 17. The wall of the depression 15 surrounding the spring 16 prevents displacement of the spring from its operative position between the arm 14 and the rail base 6.

In applying the anticreeper to the rail base, the spring 16 is first placed within the socket 15. The arm 17 is then passed beneath the rail base 6 from one side thereof in the direction of the arrow 19 in Fig. 3, while the part 8 and spring 16 are passed over the rail base. The member 7 is then forced or driven in the direction of the arrow 19, compressing the spring 16 and forcing the part 18 up against the bottom of the rail base 6 until the part 18 clears the opposite side of the rail base and snaps up into the operative position shown in the drawings. As the anticreeper is thus driven on to the rail base, the compression of the spring 16 also forces the corners 11 and 12 into gripping engagement with the rail base, and afterward the spring 16 maintains the corners 11 and 12 and the part 18 in the operative position as previously described.

When it is desired to remove the anticreeper from the rail, the part 18 is forced down below the rail base 6 and the anticreeper is then forced or driven from the rail in the opposite direction to that indicated by the arrow 19.

I claim:

1. The combination with a railroad rail having a base and a stationary part of a road bed, of an anticreeper comprising a member embracing one side of the rail base and engaging the top and bottom thereof, the lower portion of said member being adapted to engage said stationary part, and a removable spring exerting pressure against said member and said rail and tending to cant the upper portion of said member forwardly and causing said member to grip the rail base, said member being provided with means to prevent displacement of said spring.

2. The combination with a railroad rail having a base, and a stationary part of a road bed, of an anticreeper comprising a member embracing one side of the rail base and engaging the top and bottom thereof, the lower portion of said member being adapted to engage said stationary part, and a spring inserted between a part of said member and the rail base and exerting pressure against said member and the rail base and tending to cant the upper portion of said member forwardly and causing said member to grip the rail base.

3. The combination with a railroad rail having a base, and a stationary part of a road bed, of an anticreeper comprising a member embracing one side of the rail base and engaging the top and bottom thereof and having a socket formed in a part thereof, the lower portion of said member being adapted to engage said stationary part, and a spring inserted into said socket and exerting pressure against said member and the rail and tending to cant the upper portion of said member forwardly and causing said member to grip the rail base.

4. The combination with a railroad rail having a base, and a stationary part of a road bed, of an anticreeper comprising a member embracing one side of the rail base and engaging the top and bottom thereof and having a rearwardly extending arm above the rail base, the lower portion of said member being adapted to engage said stationary part, and a spring inserted between said arm and the rail base and exerting pressure against said member and the rail base and tending to cant the upper portion of said member forwardly and causing said member to grip the rail base.

5. The combination with a railroad rail having a base, and a stationary part of a road bed, of an anticreeper comprising a member embracing one side of the rail base and engaging the top and bottom thereof and having a rearwardly extending arm above the rail base, said arm having a socket formed therein, the lower portion of said member being adapted to engage said stationary part, and a spring inserted into said socket and exerting pressure against said member and the rail and tending to cant the upper portion of said member forwardly and causing said member to grip the rail base.

6. The combination with a railroad rail having a base, and a stationary part of a road bed, of an anticreeper comprising a member embracing one side of the rail base and engaging the top and bottom thereof and being provided with means to prevent displacement thereof laterally from the rail, the lower portion of said member being adapted to engage said stationary part, and a removable spring exerting pressure against said member and said rail and tending to cant the upper portion of said member forwardly and causing said member to grip the rail base, said member being provided with means to prevent displacement of said spring.

7. The combination with a railroad rail having a base, and a stationary part of a road bed, of an anticreeper comprising a member provided with a jaw embracing one side of the rail base and engaging the top and bottom thereof, said member having an arm extending beneath the rail and having

a part engaging the other side of the rail base and preventing displacement of said jaw laterally from the rail, the lower portion of said member being adapted to engage said stationary part, and a removable spring exerting pressure against said member and said rail and tending to cant the upper portion of said member forwardly and causing said member to grip the rail base, said member being provided with means to prevent displacement of said spring.

and engaging the top and bottom thereof, and said member being adapted to grip the rail base when the upper portion thereof is canted forwardly, the lower portion of said member being adapted to engage said stationary part and thereby cant the upper portion of said member forwardly, and a removable spring exerting pressure against said rail and said member and holding said member in place, said member being provided with means to prevent displacement of said spring.

8. The combination with a railroad rail having a base, and a stationary part of a road bed, of an anticreeper comprising a member embracing one side of the rail base

In testimony whereof I affix my signature hereto.

DAVID F. VAUGHAN.
